APPARATUS FOR TREATING HIDES AND SKINS.

1,158,628.

Specification of Letters Patent.

Patented Nov. 2, 1915.

Application filed May 13, 1915. Serial No. 27,950.

To all whom it may concern:

Be it known that I, WINN E. BROUGHTON, a citizen of the United States, residing in Peabody, in the county of Essex and State 5 of Massachusetts, have invented an Improvement in Apparatus for Treating Hides and Skins, of which the following description, in connection with the accompanying drawings, is a specification, like characters 10 on the drawings representing like parts.

This invention relates to apparatus for treating hides and skins, and has for its object to provide a simple and efficient machine which is capable of being used for 15 performing the operation of fleshing or unhairing or both. To this end, the machine is provided with a bed roll and with a bladed cylinder coöperating therewith; and is further provided with feed rolls which 20 are located above or at a higher level than said bed roll, with one of said feed rolls located in substantially the same plane as the bed roll and separated therefrom by a substantial space, so that the portion of the 25 hide or skin between the bed roll and feed rolls may serve as a yielding bed for an unhairing tool, which is capable of being moved into an inoperative position when the hide or skin is being fleshed, and of being moved into an operative position between the bed roll and feed roll to engage 30 the portion of the hide or skin between said rolls, when the hide or skin is to be unhaired. By providing the bladed cylinder 35 with sharp blades, the machine is capable of being used for both fleshing and unhairing, as in this case, the machine can be used for fleshing until the blades have become too dull for this purpose, whereupon the machine can be used for unhairing, or the 40 blades may be resharpened and used for fleshing, and when all of the hides or skins of a given batch or lot have been fleshed, the fleshing cylinder may be removed and 45 replaced with an unhairing cylinder. These and other features of this invention will be pointed out in the claims at the end of this specification.

Figure 1 is a rear elevation of one form 50 or construction of machine embodying this invention. Fig. 2, a side elevation of a portion of the machine shown in Fig. 1. Fig. 3, a detail in section to illustrate the unhair-

ing operation of the machine, and Fig. 4, a modification to be referred to.

55

The machine herein shown is in the main substantially the same as that shown and described in U. S. Patent No. 696,588 dated Apr. 1, 1902, and is provided with a cylinder *a* having helically arranged blades *b* to 60 act on the hide or skin *c* supported by a bed roll 10, preferably a pneumatic roll, which is mounted in a movable carriage 12 and is supplied with air pressure from a reservoir 11, substantially as shown and described in 65 U. S. Patent 854,419 dated May 21, 1907.

The carriage 12 is moved toward and from the bladed cylinder *a* by power substantially as shown and described in U. S. Patent No. 696,588 above referred to, and 70 as this portion of the machine constitutes no part of the present invention it is not deemed necessary to describe the same in detail, except to point out that 13 is the main or driving shaft and 14 the counter 75 shaft with which the carriage 12 is operatively connected, so as to be moved toward the bladed cylinder by a half revolution of the shaft 14 and to be moved back away from the bladed cylinder by the next half 80 revolution of the said shaft, after the manner described in the Patent No. 696,588 above referred to. The machine is also provided with rolls *i*, 9, *t*, corresponding to the bed roll *i*, pinch roll 9 and feed roll *t* of 85 the Patent No. 696,588, which series of rolls in the present machine are supported by the carriage 12 above the level of the bed roll 10 and bladed cylinder *a*, for which purpose said carriage is elevated or built up, as 90 herein represented. The pinch roll 9 operates in the same manner as described in the Patent No. 696,588 and is raised and lowered in curved guide ways 15, by links or arms 16, which are operatively connected 95 with the counter shaft 14. The pinch roll 9 acts to grip the hide or skin *c* between it and the rolls *i*, *t*, and said rolls are positively driven after the manner described in the Patent No. 696,588 so as to feed the hide 100 or skin out of the machine.

The roll *i* is located above the pneumatic bed roll 10 a suitable distance, so that the portion of the hide or skin *c* between said rolls is not rigidly or firmly backed up but 105 is yielding, so as to enable it to be unhaired.

by an unhairing tool, which may be of any construction suitable for this purpose and which is herein shown as a bar 20 provided with blades 21 suitable for unhairing. The 5 bar 20 in the present instance is secured to hangers 22, which are mounted to turn on a stationary shaft or rod 23 supported in uprights 24, which are erected upon the boxes 25 of the bladed cylinder *a*, and are secured thereto by screws or bolts 26 or otherwise.

10 The hangers 22 are provided with inclined arms 30, which extend upwardly from the pivot rod 23 and have attached to them rods 31, which are extended through stationary 15 arms 32 keyed or otherwise secured to the pivot rod 23. The unhairing tool or bladed bar 20 is yieldingly backed up by springs 34, which encircle the rods 31 between the arms 32 and nuts 35 on the said rods, and 20 the tension or strength of said springs may be adjusted by means of said nuts, so as to cause the unhairing tool to engage the hide or skin with the desired or required pressure. The unhairing tool 20 is arranged 25 above the bed roll 10 and bladed cylinder *a*, and engages the hide or skin between the bed roll 10 and the roll *i*, and the tension on the portion of the hide or skin *c* between the roll *i* and the bed roll 10 is sufficient to enable 30 the hide or skin to be effectively unhaired.

In operation with the apparatus herein shown, the carriage 12 is moved by power back away from the cylinder *a* and the pinch roll 9 is moved upwardly in the guide arms 35 15. The operator places the hide or skin in the machine, so that approximately one half of the hide or skin passes down between the bed roll 10 and the bladed cylinder *a*, with the fles side of the hide or skin presented to the bladed cylinder. The machine 40 is then set in motion by depressing a treadle (not shown) but in the manner described in the Patent No. 696588 above referred to, with the result that the carriage 12 is moved 45 toward the bladed cylinder and into the position shown in Figs. 1 and 3, and the pinch roll 9 is lowered into the position shown, so as to grip the hide or skin between it and the feed rolls *i*, *t*, which are provided with 50 suitable gears (not shown) for feeding the hide or skin out of the machine, while the carriage is at rest in its operative position shown in Figs. 1 and 3. The hide or skin 55 on its passage out of the machine has its flesh side acted upon by the bladed cylinder *a*, and the lumps of fat removed therefrom in the manner now commonly practised with fleshing machines. After one half of the hide or skin has been fleshed, the carriage is 60 moved back by power, and the other half of the hide or skin is placed in the machine so as to be fleshed by the cylinder *a*. During the fleshing operation, the hide or skin is supported by a substantially firm backing, 65 namely the bed roll 10, which kind of a sup-

port is essential for successful fleshing. While the hide or skin is being fleshed as described, the unhairing tool may and preferably will be held back in any suitable manner, so as to render it inactive upon the 70 flesh side of the hide or skin. The machine may be used for fleshing as long as the blades of the cylinder remain sufficiently sharp to perform this work in a satisfactory 75 manner, at which time the blades may be resharpened or ground by a suitable grinder 50, and the fleshing operation continued until the number of hides or skins desired have been fleshed, whereupon the same machine 80 may then be used to unhaire the hides or skins previously fleshed by the machine.

In the unhairing operation, the hide or skin is placed in the machine with the grain side having the hair thereon presented to the bladed cylinder *a*, and also to the unhairing tool 20, which has in the meantime been brought into its operative position. When the hide or skin is fed out of the machine, the bladed cylinder *a* acts on the haired side of the hide or skin and has a 90 double function, namely, it coöperates with the bed roll and with the feed rolls *i*, *t*, to place the portion of the hide or skin between the feed roll *i* and the bed roll 10 under tension, and second it acts to start or 95 loosen the hair, and in some cases it may remove portions of the hair. The hair which is started or loosened by the bladed cylinder *a* is removed by the unhairing tool 20, as the hide or skin is fed past the said tool. After 100 one half of the hide or skin has been unhaired, the other part or half is placed in the machine so as to be subjected to the action of the bladed cylinder *a* and the unhairing tool 20. It will be understood that 105 the blades of the cylinder are dulled sufficiently to prevent them from digging into and cutting the grain side of the hide or skin, but on the other hand, the said blades act as scrapers or pulling devices to scrape 110 or pull upon the hair and loosen the same and in some instances pull the long hairs out of the skin, and thus remove portions of the hair from some parts of the hide or skin, and the hair started or loosened by the 115 bladed cylinder *a* is removed by the unhairing tool, which acts upon the hide or skin while the latter is capable of yielding a certain amount to the pressure of the unhairing tool. The unhairing tool 20 is located 120 in proximity to the bladed cylinder, so that only a small portion of the end of the hide or skin is not unhaired by the tool 20 and this portion may be unhaired by hand. It 125 will be understood, that so far as the movements of the carriage for the bed roll, pinch and feed rolls are concerned, they are timed and governed substantially as described in the Patent No. 696588 above referred to.

From the above description it will be seen, 130

that the hide or skin can be fleshed and unhaired by the same machine, and that in this machine the fleshing tool is used on both the flesh and grain side of the hide or skin without detriment to the grain or the hide or skin. I have herein shown one construction or form of machine embodying the invention, but it is not desired to limit the invention to the particular form or construction shown. Further it is not desired to limit the invention to the particular form of fleshing and unhauling tools herein shown.

It may be preferred to utilize the skin itself as a yielding backing for the unhauling tool, but it is not desired to limit the invention in this respect as the bed roll 10 and feed roll 1 may be connected by an endless band 40, see Fig. 4, which serves as a yielding backing for the hide or skin while it is being acted upon by the unhauling tool.

The machine herein shown constitutes what may be considered a combination fleshing and unhauling machine, which is especially serviceable for tanners doing a limited business or for tanners doing a large business with a limited floor area, as in both instances a single machine may be used for either or both kinds of work, but it is also advantageous for doing either straight fleshing or straight unhauling as in this case the tanner is only required to carry an extra bladed cylinder, either fleshing or unhauling, which can be readily substituted in the machine for the bladed cylinder on the machine when the latter is purchased. When the machine is used for fleshing, the hide or skin is firmly supported by the bed roll, which is desirable for the best work, and when used for unhauling, it is provided with a yielding surface for the unhauling tool to act against, which is desirable for this work.

Claims:

1. In a machine of the character described, in combination, a bed roll, a bladed cylinder coöperating therewith, feed rolls separated from the bed roll and coöperating with the latter and said bladed cylinder to place the hide or skin under tension, and an unhauling tool to act upon the same surface of the hide or skin as the bladed cylinder and upon that portion of the hair side of the

hide or skin which is between said feed rolls and bed roll.

2. In a machine of the character described, in combination, a bed roll, a work tool coöperating therewith, a support for the hide or skin separated from said bed roll and work tool, and an unhauling tool to act on the same surface of the hide or skin as the work tool and upon that portion of the hide or skin between said support and said bed roll.

3. In a machine of the character described, in combination, a work tool, a work support coöperating therewith, one of said parts being movable toward and from the other, a work support separated from the first mentioned work support, and an unhauling tool to act on the hair side of a hide or skin between said work supports while said work tool is also acting on said hair side.

4. In a machine of the character described, in combination, a bladed cylinder, a bed roll coöperating therewith, a carriage for said bed roll movable toward and from said bladed cylinder, feed rolls mounted on said carriage above said bed roll, and an unhauling tool located above the bladed cylinder and arranged to act on the hair side of the hide or skin between said feed rolls and bed roll while the bladed cylinder is also acting on said hair side.

5. In a machine of the character described, in combination, a bladed cylinder, a bed roll coöperating therewith, a carriage for said bed roll movable toward and from said bladed cylinder, feed rolls mounted on said carriage above said bed roll, a shaft, uprights in which said shaft is mounted, hangers pivotally mounted on said shaft, an unhauling tool secured to said hangers to act on the hair side of the hide or skin between the feed rolls and bed roll, and means to yieldingly back up said unhauling tool.

In testimony whereof, I have signed my name to this specification in the presence of two subscribing witnesses.

WINN E. BROUGHTON.
